[57] CLAIM

The ornamental design for a platform body for a truck, as shown and described.

DESCRIPTION

FIG. 1 is a front elevational view of a platform body for a truck showing my new design;

FIG. 2 is a bottom plan view thereof;

FIG. 3 is a top plan view thereof;

FIG. 4 is a side elevational view thereof, the opposite side being a mirror image of that shown;

FIG. 5 is an enlarged fragmentary isometric view of one of the corners;

FIG. 6 is an isometric view thereof;

FIG. 7 is a rear elevational view thereof; and

FIG. 8 is an isometric view of a platform body for a truck showing a second embodiment of my new design, it being understood that the bottom is identical to that shown in FIG. 2 and that the opposite side and rear are mirror images of the side and front shown herein.
